CLAIM

The ornamental design for a writing desk, as shown and described.

DESCRIPTION

FIG. 1 is a rear perspective view of a writing desk according to an embodiment of the invention.

FIG. 2 is a front view of a writing desk according to an embodiment of the invention.

FIG. 3 is an overhead view of a writing desk according to an embodiment of the invention.

FIG. 4 is a rear view of a writing desk according to an embodiment of the invention; and,

FIG. 5 is an end view of a writing desk according to an embodiment of the invention, the view from the opposite end being a mirror-image thereto.

The dashed lines showing handles are for illustration purposes only and are not part of the claimed invention.
